(57) **CLAIM**

The ornamental design for a lighting assembly for imaging, as shown and described.

DESCRIPTION

FIG. 1 is a top, front, right isometric view of a lighting assembly for imaging;

FIG. 2 is a bottom, rear, left isometric view of the lighting assembly of FIG. 1;

FIG. 3 is a front elevation view of the lighting assembly of FIG. 1;

FIG. 4 is a rear elevation view of the lighting assembly of FIG. 1;

FIG. 5 is a left side elevation view of the lighting assembly of FIG. 1;

FIG. 6 is a top plan view of the lighting assembly of FIG. 1; and,

FIG. 7 is a bottom plan view of the lighting assembly of FIG. 1.

The claimed subject matter is vertically symmetrical. Accordingly, the claimed subject matter in the right side elevation view is a mirror image of the claimed subject matter in the left side elevation view, and the right side elevation view is not shown.

The broken lines in the drawings show portions of the article that form no part of the claimed design. The dash-dash broken lines in the drawings show portions of the article and form no part of the claimed design. The dash-dot broken
